[57] **CLAIM**

The ornamental design for a thermostat housing, as shown and described.

DESCRIPTION

FIG. 1 is a perspective view as seen from the front, top and right end of a first embodiment of a thermostat housing in accordance with the applicants' design with a keypad cover thereon in a closed position;

FIG. 2 is a perspective view as seen from the front, top and right end of a second embodiment of a thermostat housing in accordance with the applicants' design with the keypad cover thereon in a closed position;

FIG. 3 is a front elevation view of the thermostat housing embodiment of FIG. 1 with the cover in a closed position; FIG. 4 is a front elevation view of the thermostat housing embodiment of FIG. 2 with the cover in a closed position; FIG. 5 is a top plan view of the thermostat housing embodiment of FIGS. 1 and 3;

FIG. 6 is a bottom plan view of the thermostat housing embodiment of FIGS. 1 and 3;

FIG. 7 is a top plan view of the thermostat housing embodiment of FIGS. 2 and 4;

FIG. 8 is a bottom plan view of the thermostat housing embodiment of FIGS. 2 and 4;

FIG. 9 is a right end elevation view of the thermostat housing embodiment of FIGS. 1 and 3 with the cover in an open position;

FIG. 10 is a right end elevation view of the thermostat housing embodiment of FIGS. 1 and 3 with the cover in a closed position;

FIG. 11 is a right end elevation view of the thermostat housing embodiment of FIGS. 2 and 4 with the cover in a closed position;

FIG. 12 is a right end elevation view of the thermostat housing embodiment of FIGS. 2 and 4 with the cover in an open position;

FIG. 13 is a perspective view as seen from the front, top and right end of the thermostat housing embodiment of FIGS. 1 and 3 with the cover in an open position, and illustrating principal key switches in solid lines and optional key switches in dashed lines in the area under the cover; and,

FIG. 14 is a front elevation view of the thermostat housing embodiment of FIGS. 2 and 4 with the cover in an open position, and illustrating principal key switches in solid lines and optional key switches in dashed lines in the area under the cover.

The left end elevation views of the thermostat housing embodiments with the covers in closed and open positions are mirror images of the respective right end elevation views thereof. The rear of the thermostat housing does not comprise any portion of the invention, and hence is not shown in the drawings.
